(57) **CLAIM**

The ornamental design for the carburetor shaped novelty container, as shown and described herein.

DESCRIPTION

FIG. 1 is a top view of a carburetor shaped novelty container showing my new design, the broken line showing is for illustrative purposes only, and forms no part of the claimed design;

FIG. 2 is a bottom end view of a carburetor shaped novelty container showing my new design;

FIG. 3 is a left end view of a carburetor shaped novelty container showing my new design, the broken line showing is for illustrative purposes only, and forms no part of the claimed design;

FIG. 4 is a right end view of a carburetor shaped novelty container showing my new design, the broken line showing is for illustrative purposes only, and forms no part of the claimed design;

FIG. 5 is a side view of a carburetor shaped novelty container showing my new design, the broken line showing is for illustrative purposes only, and forms no part of the claimed design;

FIG. 6 is another side view of a carburetor shaped novelty container showing my new design, the broken line showing is for illustrative purposes only, and forms no part of the claimed design;

FIG. 7 is a perspective view of a carburetor shaped novelty container showing my new design, the broken line showing is for illustrative purposes only, and forms no part of the claimed design; and,

FIG. 8 is another perspective view of a carburetor shaped novelty container showing another embodiment of my new design, the broken line showing is for illustrative purposes only, and forms no part of the claimed design.
